UNITED STATES PATENT OFFICE.

FRANK G. PAVELEC, OF ST. LOUIS, MISSOURI.

PIPE-BOWL REAMER.

1,117,236.

Specification of Letters Patent.

Patented Nov. 17, 1914.

Application filed November 12, 1912. Serial No. 731,014.

To all whom it may concern:

Be it known that I, FRANK G. PAVELEC, a citizen of the United States, and resident of St. Louis, Missouri, have invented certain new and useful Improvements in Pipe-Bowl Reamers, of which the following is a specification.

This invention relates to improvements in pipe bowl reamers and has for its object a body arranged adjustable to fit any size pipe bowl and is for the purpose to remove the crust which cakes or adheres to the inner surface of the pipe.

Figure 1 is a perspective view of my invention shown in position in a pipe bowl. Fig. 2 is a side elevation with the upper portion in section showing its construction. Fig. 3 is an edge view of the same. Fig. 4 is a horizontal sectional view taken on the line 4—4 of Fig. 2. Fig. 5 is a plan view of the blank of which my invention is constructed. Fig. 6 is a side elevation of a modified form, the upper portion being in section showing its construction. Fig. 7 is an edge view of the same. Fig. 8 is a horizontal sectional view taken on the line 8—8 of Fig. 6. Fig. 9 is a plan view of the blank with parts broken away, of which the device is constructed.

In carrying out my invention I provide a pipe bowl reamer consisting of a body portion 10 stamped out of a strip of spring material 11, the same being bent at the point indicated by the numeral 12; the sides 13 and 14 of the strip forming the body are suitably bent as shown having a bulged portion 15, which portion is designed to contact with the inner surface 16 of the pipe bowl 17.

One end of the spring material is provided with flanges 18, which flanges are bent downwardly as shown in Figs. 2 and 3 forming a housing, or a smooth body surface against which the fingers and thumb contact for properly manipulating the device. In this body portion is arranged the adjusting feature which I will now describe.

In forming and assembling the device, the material is bent at the point indicated by the numeral 19 forming a horizontal portion 20, then bent upwardly forming a vertical portion 21 and again bent forming a horizontal portion 22; the flanges 18 on this body portion are bent downwardly at right angles to the horizontal portion forming the inclosure; the projecting end 23 is

bent downwardly and in the same and the portion 21 are formed apertures 24 in which a screw 25 has bearing; a head 26 is formed on one end of the screw, the other end being suitably swaged as indicated by the numeral 27 acting as a support for the screw retaining the same in position.

The opposite end of the strip of material is bent at the point indicated by the numeral 28 and provided with an aperture 29. The bent portion extends horizontally and is then bent downwardly forming the projection 30 in which is formed an internally screw-threaded bore 31, and by the manipulation of the screw the portion 14 of the body is adjusted wide or narrow so as to regulate the width of the bulged portion so as to accommodate various sizes of pipe bowls. The lower portions of the members 13 and 14, and from the point 12 upwardly to approximately the widest portion of the bulge is suitably ground down tapering the material sufficiently so as to permit the body to freely give at the point 12 without altering the shape of each side. The inner surface of the members 13 and 14 from the point 12 to the widest portion of the bulge is beveled as indicated by the numeral 32 forming a cutting edge 33.

The device when inserted in the bowl of a pipe is so adjusted as to permit the bulged portion to enter into the mouth of the bowl and by means of the thumb and fingers it is turned within the bowl and the cutting edges have a tendency to ream the crust from the inner wall of the pipe bowl without in any manner removing any portion of material from which the pipe is constructed, yet leaving the inner surface of the pipe bowl absolutely smooth. If the pipe should be extremely caked or the crust extraordinarily thick the operation of the reamer is repeated again and again and after the first operation the device is adjusted by means of the screw and again inserted and the action repeated.

In Fig. 6 I show a modified form, the construction being similar with the exception of the head or adjusting portion, in this instance the horizontal portion is provided with an elongated slot 34, a screw 35 supported on the horizontal portion and extending through the slot, its threaded portion 36 operating in an internally screw-threaded bore formed in the portion 37; by this construction, in order to adjust the body

the screw is manipulated with one hand and the width regulated by pressure upon the sides and when properly adjusted the screw is tightened and the body is then held in its 5 adjusted position. The cutting portion of the body in this instance instead of being beveled is perfectly straight as indicated by the numeral 38.

The device is simple in construction, is 10 cheap to manufacture and by the use of the same a pipe bowl can be thoroughly cleaned and the crust or cake on the inner wall removed.

Having fully described my invention 15 what I claim is:

1. A pipe bowl reamer, comprising a flexible body portion consisting of a pair of arms terminating in an enlarged portion having downwardly bent sides to provide a 20 housing to receive the upper end of one of said arms; a screw bolt mounted to turn in said housing, and the upper end of one of the arms; which arm is provided with a

screw thread to engage said screw bolt, substantially as specified. 25

2. A pipe bowl reamer, comprising a flexible body consisting of two arms terminating in an enlarged portion; the upper end of one of said arms provided with downwardly bent sides to provide a housing to receive the upper end of the other arm; a screw bolt mounted to turn between the downwardly bent portions and in the upper end of one of said members; which end is screw threaded to receive said screw bolt; 30 and a point formed at the apex of the joining ends of both of the arms forming said flexible member, substantially as specified. 35

In testimony whereof, I have signed my name to this specification, in presence of 40 two subscribing witnesses.

FRANK G. PAVELEC.
